(57) **CLAIM**

The ornamental design for flexible and floatable surf goggles, as shown and described.

DESCRIPTION

FIG. 1 is a front perspective view of the flexible and floatable surf goggles of the present invention, showing my new design; the broken line showing of a headband and partial leash for holding the goggles on a person, are for illustrative purposes only and form no part of the claimed design;

FIG. 2 is a top plan view of FIG. 1;

FIG. 3 is a front elevational view of FIG. 1;

FIG. 4 is a left side elevational view of FIG. 1;

FIG. 5 is a right side elevational view of FIG. 1;

FIG. 6 is a rear elevational view of FIG. 1; and,

FIG. 7 is bottom plan view of FIG. 1.
